UNITED STATES PATENT OFFICE

2,681,479

FINGER GUARD FOR SWINGING DOORS

John J. Dixon, Sr., Dorchester, Mass.

Application September 16, 1952, Serial No. 309,863

5 Claims. (Cl. 20—16)

1

The principal objects of this invention are to provide a device which is reliable in operation, which is of simple design and construction and which may readily be applied to the jamb of a door regardless of whether the door swings inwardly or outwardly, or whether it be hinged at one edge or the other, and to provide a device which does not detract from the appearance of the doorway and which can be economically manufactured.

Further objects relate to features of construction and will be apparent from a consideration of the following description and accompanying drawings, wherein:

Fig. 1 is an elevational view of what is now considered the preferred form of the invention;

Fig. 2 is an enlarged cross-section illustrating the manner in which the device is applied to a door jamb; and

Fig. 3 is a view similar to Fig. 2, but showing the door in closed position.

The device herein shown for the purpose of illustration comprises an elongated strip 1 of material such as sheet metal, extruded plastic materials or the like, preferably of L-shaped cross-section to provide a shorter leg 2 and a longer leg 3, the latter being approximately the width of the door jamb (or thickness of the door) to which it is to be applied, whereas, the shorter leg 2 approximates the depth of the jamb or recess. The shorter leg 2 is integral with a narrow resilient hinge section 4 which bends outwardly a slight amount and this section is integral with a relatively resilient scroll or tubular member 5, the diameter of which is preferably approximately the thickness of the door with which it is to be used.

As shown more clearly in Fig. 2, the center of the tubular member 5 is outwardly off-set relative to the leg 2 so that its inner surface is preferably approximately tangential to the arc defined by the swing of the door, it being understood that the inner curved surface may intersect said arc so long as it does not interfere with the closing of the door, or it may be slightly spaced from said arc provided it does not present a gap of a width which would impair its function as hereinafter explained.

The edge of the longer leg 3 is also integral with a narrow resilient hinged section 7 of which bends rearwardly slightly and this section is integral with a scroll or tubular member 8 preferably having a diameter much smaller than that of the member 5, but nevertheless sufficient to block the gap at the hinged edge of the door, as shown in Fig. 2.

2

The strip 1, whether fabricated from sheet metal or formed from extruded plastic material may be produced in lengths corresponding to the height of the doors with which they are to be used, e. g., 6'-6", 6'-8", 7'-0", etc., and prior to application to a door, the smaller scroll 8 may be cut away as indicated at 10 to accommodate the hinges H of the door D and when thus prepared the device may be readily applied to the jamb of the door as shown in Fig. 2, without removing the door from the hinges H. Nails, screws or other fastening elements may be employed to anchor the strip 1 in the jamb J of the door.

As herein shown the door D is hinged on the left hand edge (Fig. 2) and opens outwardly, but should the door be hinged on the right hand side to swing outwardly, then the strip 1 would simply be inverted; if the door were hinged on the right hand side to swing inwardly then the strip would be reversed or rotated 180°; and if hinged on the left hand side to swing inwardly, the strip would be reversed or rotated 180° in the opposite direction. Hence, it does not matter how the door is hinged.

When, as shown in Fig. 2, the door D is open the scroll 5 normally prevents the fingers F from being inserted far enough into the jamb J to be caught if the door were suddenly closed. Indeed, when the door D is being closed, its edge first contacts the fingers and the time element is such as to permit the fingers to be withdrawn due to the natural reflex action which could not be depended upon without the scroll. Even if the fingers were not immediately withdrawn upon contact with the door, the resiliency of the hinge section 4 and/or the scroll 5 would prevent the application of injurious squeezing or crushing force. The same is likewise true of the smaller scroll 8 which substantially blocks the gap between the hinged edge of the door and the jamb surface.

While I have shown and described one desirable embodiment of the invention, it is to be understood that this disclosure is for the purpose of illustration and that various changes and modifications may be made without departing from the spirit and scope of the invention as set forth in the appended claims.

I claim:

1. A device for preventing the fingers from being accidentally caught in the jamb of a door comprising an elongate strip of material having a width approximately equal to that of the jamb of the door to which it is to be applied, one longitudinal edge of said strip being integral with

a relatively resilient scroll having a diameter approximating the width of the jamb, said scroll extending outwardly from said door jamb and being so disposed that its curved surface adjacent to said door is substantially tangential to the arc defined by the inner edge of said door.

2. A device for preventing the fingers from being accidentally caught in the jamb of a door comprising an elongate strip of material having an L-shaped cross-section, the width of the longer leg being approximately equal to that of the jamb of a door to which it is to be applied, said scroll extending outwardly from said door jamb and being so disposed that its curved surface adjacent to said door is substantially tangential to the arc defined by the inner edge of said door, the edge of the shorter leg of said strip being integral with a scroll having a diameter approximating the width of the gap between the door jamb and hinged edge of the door when the door is open.

3. A device for preventing the fingers from being accidentally caught in the jamb of a door comprising an elongate strip of material having an L-shaped cross-section, the width of the longer leg being approximately equal to that of the jamb

of a door to which it is to be applied and the width of the shorter leg being approximately equal to the depth of said jamb, the edge of the shorter leg of said strip being integral with a scroll having a diameter approximating the width of the jamb surface, said scroll extending outwardly from said door jamb and being so disposed that its curved surface adjacent to said door is substantially tangential to the arc defined by the inner edge of said door, the edge of the longer leg being integral with a scroll having a diameter approximating the width of the gap between the door jamb and hinged edge of the door when the door is open.

4. A device as set forth in claim 1 fabricated from sheet metal.

5. A device as set forth in claim 1 made from extruded plastic material.
